UNITED STATES PATENT OFFICE.

JOHN NONNENBACHER, OF NEW YORK, N. Y.

DESIGN FOR ORNAMENTAL MOLDINGS.

Specification forming part of Design No. 7,460, dated May 26, 1874; application filed March 6, 1874.
[Term of Patent 3½ years.]

To all whom it may concern:

Be it known that I, JOHN NONNENBACHER, of the city, county, and State of New York, have invented a Design for a Mirror, Picture-Frame, Cornice, and other Moldings, of which the following is a specification:

The nature of my design is fully represented in the accompanying drawing, to which reference is made, and in which—

Figure 1 represents a face elevation, and Fig. 2 a cross-section.

a represents a molded portion brought well forward, convex surface, and ornamented with raised bunches of grapes, vines, leaves, &c. *b* represents a convex portion, plain. *c* represents a flat portion, slanting at an angle, and ornamented with a burnished stenciled ornament or figure. *d* represents an ogee portion,

having an ornamentation raised, as shown. *e* represents a slightly-convex portion with flat stenciled ornamentation. *f* represents a molded portion projecting well forward and plain. *g* represents a small ornamented portion, ornaments raised.

The ornamented parts *a*, *d*, and *g* are in gilt, and the flat ornamented parts *c* and *e* are in silver gilt, the stenciling being in bronze or gilt. All the remainder of the parts composing the molding or moldings are in silver gilt.

What I claim as my invention is—

The design for moldings, frames, cornices, &c., as herein shown and described.

JOHN NONNENBACHER.
